UNITED STATES PATENT OFFICE.

SALVATORE ZODA, OF TRENTON, NEW JERSEY.

SKIM GATE.

Application filed April 14, 1926. Serial No. 102,015.

This invention relates to skim-gates for casting molds, and has for its object the construction of novel means of the class described for separating the dross or slag from 5 the molten metal as it is poured into the mold, in a manner more efficient and complete than has hitherto been accomplished with devices designed for this purpose.

More specifically, the object of the invention 10 is to provide a multi-part skim-gate which when assembled forms upper and lower chambers, in the former of which the grosser slag collects, while the lower chamber functions to collect and separate from 15 the molten metal the finer order of slag or dross which may pass through the perforated skimming plate.

The invention has for its further object 20 the provision as part of the skim-gate, of an offset receiving hopper into the remote end of which the metal may be poured from the ladle, the same flowing laterally through the in-gate passage instead of dropping into it from a height as in ordinary practice, 25 thereby avoiding forcing the dross downwardly through the body of metal in the skim-gate by sheer velocity of the inflow.

Other objects of the invention will appear 30 as the following description of a preferred embodiment thereof proceeds.

In the drawings:—

Fig. 1 is a vertical section through a two-part mold and the skim-gate associated therewith, said skim-gate embodying the 35 principles of the present invention.

Figs. 2, 3 and 4 show consecutively, perspective views of the upper, intermediate and lower members of the skim-gate.

Fig. 5 is a section taken along the line 40 5—5 of Fig. 1.

Referring now in detail to the several figures, the numerals 1 and 2 represent respectively the cope and drag, together forming a two-part mold, filled with molder's 45 sand in the usual manner, having the un-filled space 3 into which the metal is to be run to form the casting. The sand in the drag is formed with a lateral passage 4 communicating with the space 3 and with 50 the skim-gate. The latter consists essentially of three parts arranged in a vertical tier embedded in the sand of the cope, and preferably a fourth part, the receiving hopper 6 which rests upon the surface of the sand within the cope and communicates with 55 the in-gate passage.

The three embedded parts include the skimming tray 7 having a peripheral flange and dished center, the latter being formed with perforations 8, preferably cylindrical. 60 Beneath the skimming tray is the frusto-conical well 9 having the upper edge thereof registrable with the flange of the skimming tray and converging downwardly, terminating in a relatively small outlet aperture 10. 65 Above the skimming tray and also registrable with the peripheral flange thereof is the dome 11 having a frusto-conical chamber 12 the walls of which converge upwardly, terminating in a passage 13 which opens 70 in the upper face of the dome and is adapted to communicate with the in-gate passage 5 of the hopper.

These parts are shown in assembled relation in Fig. 1, in which it will be observed 75 that the hopper 6 is offset with respect to the in-gate passage, it being the intent of the invention that the metal shall be poured into the in-gate passage. It is obvious that the hopper can be oriented in any direction 80 to suit the convenience of the operator.

The metal flowing through the in-gate 85 passage 5 and passage 13 collects in the dome faster than it can pass through the perforations 8, forming a body of molten metal in the dome chamber from which the dross or slag separates, floating to the surface of the metal and lying upon it in a layer of greater or less thickness according to circumstances. Since the metal flows into the 90 in-gate passage laterally, and without having acquired a head as would be the case were it dropped from a height directly into the in-gate passage from the ladle, the dross or slag will not be driven downwardly into 95 the body of molten metal in the dome chamber but will rise to the surface with very little opposition from the inflow of metal. The overhanging wall of the dome chamber forms an annular space of minimum turbulence around the current of descending metal, giving the dross or slag a chance to rise without being re-entrained with the descending metal. Most of this slag collects 100 upon the wall of the dome chamber and is discarded, with the dome 9 after the casting 105 has been made.

The aggregate area of the apertures in the skimming tray is so related to the outlet aperture 10 of the well chamber that metal 110 flowing through the skimming tray backs up in the well 9 forming a body of molten

metal with a space above it and below the skimming plate into which dross or slag of the finer order collects. The upwardly divergent wall of the well chamber forms an annular space of minimum turbulence around the perforated area of the skimming tray, in which a portion of the slag which may pass through the tray 7 freely accumulates, adhering to the wall of the well so that it, too, may be thrown away when the well is discarded.

The chamber 12 with the upwardly converging walls, as heretofore explained, serves to retain the greater portion of the slag and other impurities, and very little of the slag passes through the tray 7 into the well or lower chamber 9 which converges downwardly, the latter chamber distinctively serving to break up the pockets or balls of gas that pass through the said tray 7 with the molten metal, so that when the latter metal passes through the outlet aperture 10 it is practically clean or free of slag or dirt accumulations and gas and passes into the mold cavity or space 3 by way of the passage 4 in a practically clean or purified condition, and as a consequence a much better quality of casting results in finally treating castings to render them fit for service. The invention is not in the least limited to the use of the hopper 6, as any inlet means may be employed in communication with the inlet passage or opening 13. When the molten metal is admitted through the inlet passage 13 into the conical chamber 12 it assumes a whirling motion and thereby forces the slag and other impurities outwardly towards the wall of said chamber 12, and when the charge of metal thus admitted passes through the tray 7 it continues to have a whirling motion in the chamber of the well or lower chamber 9, which is converged towards the bottom outlet opening or aper-

ture 10, said movement of the molten metal in the well or lower chamber 9 forcing the gases outwardly towards the wall of the said lower chamber together with a comparatively small portion of the slag that may pass through the tray 7, and as a consequence the metal flowing into the passage 4 is practically free of slag and other dirty accumulations and gas, with the result that the casing formed in the space or cavity 3 is pure and has a homogeneity of texture.

It is contemplated that the several parts of my improved skim-gate shall be made of molder's sand baked in the usual manner and that they may be discarded after having been used once.

While I have in the above description defined what I believe to be a practical and preferred form of my invention, yet it is to be understood that the specific details in which the invention is disclosed are not limitative in their effect upon the invention, but merely by way of example, except where they are prescribed by the express terms of the appended claim.

Having described my invention what I claim as new and desire to secure by Letters Patent, is:—

A skim-gate for casting molds, comprising an upper member having a conical chamber provided in its top with a central inlet, a lower member having an inverted conical chamber provided in its bottom with a central outlet, both upper and lower chambers being otherwise imperforate, and an intermediate perforate tray having an upper concave side and a lower convex side and closely fitting between said upper and lower members.

In testimony whereof I have hereunto set my hand.

SALVATORE ZODA.
